UNITED STATES PATENT OFFICE.

ARTHUR SMITH DWIGHT, OF KANSAS CITY, MISSOURI, AND RUDOLF RUETSCHI, OF ARGENTINE, KANSAS.

CURTAIN FOR DUST-COLLECTING APPARATUS.

SPECIFICATION forming part of Letters Patent No. 655,547, dated August 7, 1900.

Application filed October 9, 1899. Serial No. 733,073. (No model.)

To all whom it may concern:

Be it known that we, ARTHUR SMITH DWIGHT, of Kansas City, in the county of Jackson and State of Missouri, and RUDOLF 5 RUETSCHI, of Argentine, in the county of Wyandotte and State of Kansas, have invented a new and Improved Curtain for Dust-Collecting Apparatus, of which the following is a full, clear, and exact description.

- 10 The invention relates to fume-arresters for mechanically precipitating and collecting metallic fumes and flue-dust in metallurgical establishments; and its object is to provide a new and improved curtain for dust-collecting apparatus, to insure a thorough and quick collection of the solid matter carried by the furnace or other gases and fumes and arranged so that a given effect can be produced with a shorter flue, the weight of metal necessary for the curtains be much diminished, lighter construction be used in supporting the curtains, and, in short, a considerable cheapening of the cost of construction can be effected with greatly-increased efficiency.
- 15 The invention consists of novel features and parts and combinations of the same, as will be fully described hereinafter and then pointed out in the claims.

A practical embodiment of our invention 20 is represented in the accompanying drawings, forming a part of this specification, in which similar characters of reference indicate corresponding parts in all the views.

Figure 1 is a sectional plan view of the improvement on the line 1 1 in Fig. 2. Fig. 2 is 25 a sectional side elevation of the same on the line 2 2 in Fig. 3, and Fig. 3 is a cross-section of the same on the line 3 3 in Fig. 2.

In the chimney-flue A are arranged sets of 30 curtains B, supported on suitable cross-bars C and reaching from the top or arch of the flue A a short distance below the upper ends of the cross-dams D for protecting the flue-dust already collected in the bottom of the 35 flue from longitudinal movement therein by the action of the current of the gases travelling through the flue in the direction of the arrow a'—that is, in a direction parallel to the curtains B. Each curtain B is formed of 40 sets of members B', each set being hung on longitudinal rods B², supported by cross-

bars C, attached at their ends in the side walls of the flue A. The members B' are arranged approximately parallel to one another, but stand obliquely to the direction of travel 55 of the gases in the flue A, each member presenting oblique surfaces or facets to the longitudinal currents of the gases between adjacent curtains to divide such current into a large number of smaller oblique currents to 60 form eddies or whirls at or in close proximity to the said surfaces or facets to insure a thorough and quick mechanical precipitation of the solid matter in the gases on said surfaces or facets, it being understood that by 65 forming each curtain of a large number of members disposed obliquely to the current of the gases a large increase of frictional surface in the flue is had within a comparatively short length of flue, and as the collecting efficiency of the device depends mainly on the frictional area it is evident that with our construction the desired result is readily attained. The deposit of solid matter on the members B' clings to the latter until the 70 weight of the matter overbalances its adhesive force, when the matter will drop and gather on the floor of the flue between adjacent dams D to be removed from time to time by proper appliances. The curtains in succeeding sets are preferably arranged out of alignment, as plainly indicated in Fig. 1, thus again breaking up the gas-currents between such sets, thereby tending to more thoroughly mix the gases between successive sets of curtains. As the currents of gases pass between the individual curtains in a set the solid matter or dust is precipitated on the surface of the members by friction, as is well known in 75 devices of this class; but this precipitation is greatly increased by disposing the individual members of each curtain obliquely to the current to produce the whirls or eddies, as before stated.

We do not limit ourselves to the particular 80 construction and arrangement of the curtains as shown in the drawings, as it is evident that the same effect may be accomplished by using as curtains panels or frames strung with parallel narrow ribbons, of metal or other 85 material, having the plain surfaces turned obliquely to the plane of the panel, but practi-

cally parallel to one another. These curtains or panels will then be hung parallel one to the other in the flue in alinement with the direction of the current, so as to split up the latter, as already described, into parallel currents between the members.

In devices of this class as heretofore constructed sheet-metal plates or longitudinal curtains were suspended in the flue parallel to the direction in which the gases were traveling—as, for instance, as shown and described in the Letters Patent of the United States No. 276,386, granted to Max Freudenberg, dated April 24, 1883. These plates are spaced uniformly across the flue and extend from the floor to the crown of the arch, so as to split up the gases uniformly into parallel currents and expose as large a surface for frictional contact as may be deemed necessary for the purpose of collecting the flue dust and fumes. The gases leave a deposit of material clinging to these plates, and which deposit in course of time falls off by its weight and gathers on the floor of the flue, from whence it is removed by proper appliances, the same as in our apparatus as above described. We are also aware that curtains of wire-netting have been substituted for sheet metal; but we do not claim such construction nor the use of plates, as described in the patent referred to.

Having thus fully described our invention, we claim as new and desire to secure by Letters Patent—

35 1. A curtain for dust-collecting apparatus, comprising a support, and a series of parallel vertical members carried by the support, said members being arranged obliquely to a vertical plane passing through the support and spaced apart, forming passages between adjacent members, as and for the purpose set forth.

40 2. A curtain for dust-collecting apparatus, comprising a supporting rod or bar, and a series of vertical members carried by the bar or rod, said members being arranged obliquely to the bar or rod and spaced apart, whereby a curtain with a series of inclined passages will be formed, substantially as described.

45 3. In a dust-collecting apparatus, the com-

bination with a flue, of a series of curtains arranged longitudinally in the flue, each curtain being formed of a series of obliquely-arranged and spaced vertical members, substantially as described.

55

4. In a dust-collecting apparatus, the combination with a flue, of a series of curtains arranged longitudinally in the flue, each curtain comprising a horizontal rod, and a series of vertical members hung on the rod to project on either side thereof, said members being arranged obliquely to the rod and spaced apart, substantially as described.

60

5. In a dust-collecting apparatus, the combination with a flue having dams in its bottom, of a series of curtains arranged longitudinally in the flue, and extending from the top of the flue to a short distance below the upper ends of the dams, each curtain being formed of a series of members arranged obliquely to the length of the flue and spaced apart, substantially as described.

65

6. In a dust-collecting apparatus, the combination with a flue, of a series of curtains arranged in sets in the flue and extending longitudinally thereof, the sets of curtains being out of alinement, and each curtain formed of a series of members spaced apart and arranged obliquely to the length of the flue, substantially as described.

70

7. The combination with a flue having dams in its bottom, of a series of curtains arranged longitudinally in the flue and extending from the top of the flue to a short distance below the upper ends of the dams, each curtain comprising a rod, and a series of members carried by the rod and projecting on either side of the same, said members being arranged obliquely to the rods and spaced apart, substantially as described.
